ATTORNEY.

UNITED STATES PATENT OFFICE

139,015

DESIGN FOR A SHIP LADDER RUNG UNIT

Ingolf Karlsen, New York, N. Y.

Application July 25, 1944, Serial No. 114,557

Term of patent 14 years

(Cl. D15—8)

To all whom it may concern:

Be it known that I, Ingolf Karlsen, a citizen of the United States, residing at 8 State Street, New York City, county and State of New York, have invented a new, original, and ornamental Design for Ship Ladder Rung Unit, of which the following is a specification, reference being had to the accompanying drawing, forming part thereof, and in which:

Figure 1 is a front elevational view of a ship ladder rung unit, showing my new design.

Figure 2 is an end elevational view of Figure 1.

Figure 3 is a top plan view of Figure 1.

Figure 4 is a sectional view looking towards the inside of one of the ladder elements; while

Figure 5 is a sectional view taken on the line 5—5 of Figure 4.

The dot-and-dash lines in several figures of the drawing represent ropes and are illustrative only.

I claim:

The ornamental design for a ship ladder rung unit, as shown and described.

INGOLF KARLSEN.
